UNITED STATES PATENT OFFICE.

HERBERT WILLIAM HELLIKER, OF OAKLAND, CALIFORNIA.

CARD-EXHIBITING DEVICE.

1,088,574.

Specification of Letters Patent. Patented Feb. 24, 1914.

Original application filed November 8, 1912, Serial No. 730,163. Divided and this application filed June 20, 1913. Serial No. 774,811.

To all whom it may concern:

Be it known that I, HERBERT W. HELLIKER, a subject of the King of Great Britain, and a resident of Oakland, in the county of Alameda and State of California, have invented a new and Improved Card-Exhibiting Device, of which the following is a full, clear, and exact description.

This invention relates to display apparatus, and especially to devices for holding and exhibiting cards or the like.

The particular object of this invention is to provide an exhibiting device for cards for use in connection with certain game apparatus made the subject of a previous application filed by me on November 8, 1912, Serial No. 730,163, and allowed on April 8, 1913, and of which this application is a division.

20 The foregoing and other objects of the invention will hereinafter be more fully described and claimed and illustrated in the drawings forming a part of this specification in which like characters of reference indicate corresponding parts in all the views, and in which—

Figure 1 is a front elevation of a cabinet or casing having a series of openings or windows; Fig. 2 is a vertical section of the same; Fig. 3 is an enlarged longitudinal section through one of the holders; and Fig. 4 is a transverse section on the line 4—4 of Fig. 3.

The several parts of the device may be 35 made of any suitable materials and the relative sizes and proportions of the same may be varied to a considerable extent without departing from the spirit of the invention hereinafter more fully set forth and specifically claimed.

In Figs. 1 and 2 the support or casing 10 is of any suitable construction of upright nature and provided with a semi-cylindrical horizontal forwardly projecting extension 45 11. This extension is provided with one or more windows or openings 12, shown herein as five in number, and within said extension 11 and just in the rear of each of said windows 12 is a cylindrical roller 13. Each 50 roller is journaled at its ends upon trunnions 14 and 15 suitably fixed in any convenient frame members 16 and 17, respectively, of the apparatus. A gear wheel shown as a sprocket 18 is secured adjacent one end of 55 the roller 13, and a chain 19 operates there-

over from any suitable source of power whereby the roller may be rotated, as desired, around the axis of the trunnions 14 and 15. A cup 20 is preferably arranged in each end of the roller for the reception and holding of anti-friction rollers 21. Each roller, furthermore, is provided with a plurality of longitudinal parallel kerfs or grooves 22 extending preferably entirely around its circumference. At 23 I show pictures or cards of any suitable nature adapted to be connected to the rollers and to be displayed at any suitable intervals through said windows. Each card, and by the term "card" as used hereinafter I would 60 wish to be understood as covering any sort of picture or any device of a similar nature to be displayed, is adapted to be held individually, preferably at one end, in a holder 65 24. Said holder comprises two principal parts, namely, a shank 24^a and a clamp 24^b hinged together by means of a pivot 25. The shank is fitted into one of said kerfs 22 and is formed at its ends with cutaways or shoulders 26, the outer edges of which lie 70 substantially flush with the circumference of the roller. Each card is held in its clamp either by friction or by some positive fastener, such as shown at 27. After the card holders are all inserted into the respective 75 kerfs, a pair of straps or bands 28 are put around the ends of the roller engaging all of said shanks at said shoulders, securing 80 them from outward displacement, and the same are prevented from longitudinal displacement in the kerfs by means of the end plates 30 which serve also as keepers for the anti-friction rollers 21 surrounding the trunnions 14 and 15.

Assuming that the roller is caused to rotate in the direction indicated by the arrow on Figs. 2 and 4, the respective holders will be rotated accordingly, causing the cards to be carried around the axis thereof. Each card is acted upon by means of a leaf spring 31 which has a tendency to lift the card while it is rising at the rear of the roller so as to cause the same to come into engagement with a projection 32 at the upper portion of the window extension 11 whereby the 85 several cards are retarded momentarily while the roller rotates, or, if the roller is caused to rotate intermittently, one of the cards of each roller will be held in view through its window.

Having thus described my invention, I claim as new and desire to secure by Letters Patent:

1. In a card exhibiting device, the combination of a cylindrical roller, stationary means coöperating with the ends of the roller to support the roller in position, means connected to the roller to rotate the same around said fixed supports, said roller being provided with a series of parallel kerfs extending from one end thereof to the other and said series extending around the cylindrical surface thereof, and a holder for a card seated in each of said kerfs, said holder including a relatively stationary shank seated as aforesaid and a clamp pivoted to said shank, the card holder being substantially the same length as the roller.
2. In a card exhibiting device, the combination of a roller, means to pivotally support the same on its longitudinal axis, means connected to one end of the roller to control its rotation, said roller being provided with one or more longitudinal kerfs extending thereinto, a card holder including a shank seated in each of said kerfs and having

shoulders lying flush with the surface of the roller, said holder also including a clamp for a card, and means surrounding the roller and coöperating with said shoulders to maintain the card holders in position.

3. In a card exhibiting device, the combination with a casing having a window and a projection adjacent thereto, of a roller within the casing, means to support the roller for rotation in the rear of said window, a series of card holders secured in parallel relation to one another to the roller, each card holder comprising a relatively stationary shank, a clamp pivoted thereto, and a spring having its free end acting upon the pivoted clamp tending to lift the card while it is ascending with the roller and to cause the same to come into coöperation with the aforesaid projection, and means to control the rotation of the roller.

In testimony whereof I have signed my name to this specification in the presence of two subscribing witnesses.

HERBERT WILLIAM HELLIKER.
